UNITED STATES PATENT OFFICE.

WASHINGTON G. COXWELL, OF BRADLEY, ALABAMA.

DESIGN FOR A GRAVESTONE.

41,446.

Specification for Design.

Patented June 6, 1911.

Application filed April 8, 1911. Serial No. 619,916. Term of patent 7 years.

To all whom it may concern:

Be it known that I, WASHINGTON G. COXWELL, a citizen of the United States, residing at Bradley, in the county of Escambia and State of Alabama, have invented a new, original, and ornamental Design for Gravesstones, of which the following is a specification, reference being had to the accompanying drawings, forming a part thereof.

The figure is a perspective view of a gravestone showing my new design.

I claim:

The ornamental design for a gravestone as shown.

WASHINGTON G. COXWELL.

Witnesses:

W. E. BUCKHALTS,
G. W. KILPATRICK.
